UNITED STATES PATENT OFFICE.

OLIVER WARREN JOHNSON, OF OAKHARBOR, OHIO.

DESIGN FOR A CAR-REPLACER.

SPECIFICATION forming part of Design No. 34,906, dated August 6, 1901.

Application filed October 11, 1900. Serial No. 32,791. Term of patent 14 years.

To all whom it may concern:

Be it known that I, OLIVER WARREN JOHNSON, a citizen of the United States, residing at Oakharbor, in the county of Ottawa and

5 State of Ohio, have invented and produced a new and original Design for a Car-Replacer; and I do hereby declare the following to be a full, clear, and exact description of the invention, such as will enable others skilled in the art to which it appertains to make and use the same.

This invention relates to a design for a car-replacer which in general outline is approximately of triangular form, having its top surface in different planes, the forward plane being horizontal and substantially triangular and the rear planes sloping and of trapezoidal shape and separated by a saddle whose sides are right-angled triangles and whose 15 top is about in the plane of the upper forward portion of the body. Ribs project vertically from the longitudinal edges of the triangular-shaped body, and the sides of the body have their top edges conforming to the profile of 20 the top and their lower edges straight and formed with horizontal flanges.

In the accompanying facsimile-drawings of the design, Figure 1 is a perspective view. Fig. 2 is a top plan view. Fig. 3 is a rear 25 view. Fig. 4 is a side elevation. Fig. 5 is an end view.

Corresponding and like parts are referred to in the following description and indicated in all the views of the drawings by the same reference characters.

35

In plan view the car-replacer is approximately of triangular form, and its top is composed of three planes or surfaces 1 2 3, the plane 1 being horizontal and triangular in form and the planes 2 and 3 being trapezoids 40 and rearwardly inclined from the plane 1. A saddle 4 separates the planes 2 and 3, and its top is about on a level with the plane 1, and its sides 5 are right-angled triangles. Ribs 6 and 7 project vertically from the longitudinal edges of the body, and the sides 8 have their top edges conforming to the profile of the top of the body and their lower edges straight and formed with horizontal flanges 45 9. The converging ends of the ribs 6 and 7 50 curve inwardly and have a valley between them.

Having thus described the invention, what is claimed as new is—

The design for a car-replacer, substantially 55 as herein shown and described.

In testimony whereof I affix my signature in presence of two witnesses.

OLIVER WARREN JOHNSON. [L. S.]
